(57) **CLAIM**

The ornamental design for an electric connection terminal, as shown and described.

DESCRIPTION

1.1: Perspective

1.2: Front

1.3: Back

1.4: Left

1.5: Right

1.6: Top

1.7: Bottom

1.8: Cross-sectional

1.9: Cross-sectional

4.1: Perspective

4.2: Front

4.3: Back

4.4: Left

4.5: Right

4.6: Top

4.7: Bottom

4.8: Cross-sectional

4.9: Cross-sectional

These articles are made of electrically conductive material; one or more electric wires can be connected electrically to an external electric wire or even without removing insulating covers of one or more electric wires; the vicinity of through holes is coated with an electrically conductive material by thermal spraying so that the end parts of the electric wires are electrically connected to this article; the external electric wire connects to the connecting part (hole) on one side of this article. In the reproductions, the broken lines are for the purpose of illustrating portions of the article that form no part of the claimed design. The electric connection terminal is shown with a symbolic break in its length. The appearance of any portion of the article between the break lines forms no part of the claimed design; **1.8** and **4.8** are cross-sectional views cut vertically at the center of the connecting hole; **1.9**, and **4.9** are cross-sectional views cut vertically at the center of the groove.

1 Claim, 18 Drawing Sheets
